MANUAL FLOOR WAXER AND POLISHER

Alpoim Corrêa, Rio de Janeiro, Brazil

Application June 23, 1944, Serial No. 541,832
In Brazil December 20, 1943

3 Claims. (Cl. 15—27)

1

The present invention refers to a manual floor waxer and polisher, with which the waxing and polishing of floors can be more easily, economically and efficiently performed than with any of the other types of polishers known to date.

Up to now the rotation of the brushes of a floor polisher has only been accomplished by means of a motor incorporated with the polisher and connected through a plug to an electric outlet.

The polisher of the present invention is also provided with rotating brushes; however, their rotation is simply obtained by the friction of the brushes against the floor surface, as the usual back and forth movement is given to the polisher.

In order to attain this result, two or more circular brushes are mounted in the under side of the body of the polisher, in such a manner that each of them is free to rotate around a corresponding approximately vertical axis and that all of them oscillate with limited small amplitude around corresponding horizontal axis which cross through the respective approximately vertical rotating axis. Each brush is combined with a conveniently adapted spring which act, by utilizing the limited oscillation allowance of the brushes around their respective horizontal axis, to force the under surfaces of said brushes to be on different planes forming wide obtuse angles, the imaginary edges of which are parallel to the horizontal axis.

When the polisher of the present invention is moved back and forth on the floor in the usual manner, the following occurs: in opposition to the action of the springs which tend to maintain the brushes on different planes, the polisher by its own weight forces the under surfaces of said brushes to be all on the same plane in contact with the surface of the floor to be waxed or polished; however, due to the stress of the springs, the pressure exerted by the brushes on the floor is not uniformly distributed over their entire under surface, and is greater at successive points of their circumferences as the polisher is moved back and forth.

The present invention further includes certain preferred constructive details, as may be noted from the following description made with reference to the attached drawing, in which a preferred embodiment of the invention is exemplified. In this drawing

Figure 1 is a perspective view showing the general appearance of a floor polisher built in accordance with the invention and provided with three brushes;

2

Figure 2 represents a vertical cross section of same polisher; and

Figure 3 is a bottom view of the polisher, in which one of the brushes has been removed and another is shown without its respective felt disc.

- With reference to the drawing, 1 is a frame provided in its under side with circular recesses 2 which form salient portions 3 on its upper side. The central part of a double-arm crosshead 4—4a is fitted into each of these recesses. Both sides of the longer arm 4 bend downwards in right angle forming short vertical sections, after which they bend back in right angle to the horizontal position; both ends of these longer arms 4 are inserted in corresponding notches provided for this purpose in projections 5 of the frame 1. The other arm 4a of the crossheads is shorter and serves to limit the oscillation amplitude of said crossheads by the fact that both of its free ends hit against the under side of recesses 2. The end of the longer arm 4 of each crosshead, closer to the external lateral side of frame 1, is connected to one of the ends of a cylindrical spiral spring 6 having its other end fixed to a screw 7 which is threaded in frame 1 from the outside. By turning more or less this screw 7 it is possible to increase or decrease the tension of spring 6 and consequently to regulate the spring pressure of the crosshead 4—4a.
- 10 A vertical axis 8 projects downwards from the center of each crosshead 4—4a and fits into a base supporting the brush 9; this base consists of a conical lubricating box 10 with a cover 11, containing an oil soaked felt 12, and is provided with a central tube 13, closed at its bottom, into which the axis 8 is inserted. The lower end of said axis 8 has a concave surface which sets on a metallic ball 15 placed at the bottom of said tube 13 in order to facilitate the rotation of box 14 around axis 8.
- 15 Each conical box 10 is provided at a certain point with a long screw 14 extending across said box and penetrating into tube 13 through an orifice 13a; the point of this screw 14 projects into an annular groove 8a in the vertical axis 8. The purpose of said screw 14 is to hold box 10 in position around said axis 8 without preventing its rotation. The diameter of orifice 13a is somewhat larger than that of screw 14 in order to permit the passage of the lubricant from conical box 10 into tube 13. The annular groove 8a is relatively wide in order to allow a certain vertical leeway of box 10 in relation to axis 8, so that when the polisher is lifted from the floor said box 10 falls by its own weight to the point where

the lower side of groove 8a is held by the free end of screw 14, whereas when the polisher rests on the floor said box 10 raises along axis 8 to the point where the upper side of groove 8a is retained by the free end of screw 14.

The lower part of box 10 is provided with a horizontal disc 16 projecting outwardly which supports a circular brush 9. Tube 13 extends downwards from said box 10 and its lower end may be inserted by pressure into a tubular member 17 carrying a felt disc 18 which adapts itself to the under surface of the brush.

Similarly to other usual types of floor polishers, the polisher of the present invention is provided with an oscillating handle 19. This handle is provided with a latch 20 which may be fastened in a notched projection 21 on the upper side of frame 1, in order to facilitate the portability of the floor polisher.

It will be understood that the present invention is not limited to the above described form of construction, which is merely a preferred form, but on the contrary it is intended to include any modifications made within the spirit of the invention and of the characteristic points mentioned in the following claims.

I claim:

1. A manual floor waxes and polisher including two or more circular brushes, a frame with relation to which the said brushes operate, said frame having circular recesses on its face formed by salient portions on its upper side, a double-arm cross head fitted in each recess and each having a vertical axis, one of the cross arms being shorter than the other, the longer cross arm having its ends journalled in the frame at opposite sides of the recess, means for yieldingly holding the cross arm and its vertical axis tilted, the said shorter cross arm serving to engage the top wall of the recess for limiting the tilting action, and means by which the brush is rotatably mounted on the vertical axis.

2. A manual floor waxes and polisher including two or more circular brushes, a frame with rela-

tion to which the said brushes operate, said frame having circular recesses on its face formed by salient portions on its upper side, a double-arm cross head fitted in each recess and each having a vertical axis, one of the cross arms being shorter than the other, the longer cross arm having its ends journalled in the frame at opposite sides of the recess, means for yieldingly holding the cross arm and its vertical axis tilted, the said shorter arm serving to engage the top wall of the recess for limiting the tilting action, and means by which the brush is rotatably mounted on the vertical axis, said means consisting of a conical lubricating box provided with a cover for containing a lubricant and said box being provided with a central tube closed at its bottom into which tube the vertical axis is inserted, and means for holding the parts assembled.

3. A manual floor waxes and polisher including two or more circular brushes, a frame with relation to which the said brushes operate, said frame having circular recesses on its face formed by salient portions on its upper side, a double-arm cross head fitted in each recess and each having a vertical axis, one of the cross arms being shorter than the other, the longer cross arm having its ends journalled in the frame at opposite sides of the recess, means for yieldingly holding the cross arm and its vertical axis tilted, the said shorter cross arm serving to engage the top wall of the recess for limiting the tilting action, means by which the brush is rotatably mounted on the vertical axis, said means consisting of a conical lubricating box provided with a cover for containing a lubricant and said box being provided with a central tube closed at its bottom into which tube the vertical axis is inserted, an annular groove formed in the vertical axis, and a screw extending through the lubricating box and having its end projecting into the annular groove permitting axial movement of the vertical axis and retaining the parts assembled.

ALPOIM CORRÊA.
